DRIVING MECHANISM

Filed Oct. 9, 1941

FIG. 1.

UNITED STATES PATENT OFFICE

2,345,418

DRIVING MECHANISM

Martin Neuner, Fairview, N. J., assignor to Bendix Aviation Corporation, South Bend, Ind., a corporation of Delaware

Application October 9, 1941, Serial No. 414,373

3 Claims. (Cl. 192—02)

This invention relates to driving mechanism, and particularly to mechanism for coupling a rotating element with an element to be rotated therewith.

An object of the invention is to provide novel electromagnetic coupling means, in a device of the character described.

A second object is to provide, in an electromagnetic driving mechanism, novel means for delivering energizing current thereto.

Another object is to provide, in an electric motor driven clutch mechanism, means for utilizing the motor structure as the vehicle for delivery of energizing current to the clutch.

Another object is to provide a clutch mechanism having elements thereof rotatable with the armature of a driving motor, one of which rotatable elements is a clutch-engaging, electromagnetic coil whose end portions pass through slots in the armature, and connect with the commutator portion in such manner that the commutator segments constitute terminals for the coil.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing,

Fig. 1 is a view, partly in mechanical section and partly diagrammatic, of apparatus embodying the invention; and

Fig. 2 is a more complete diagram of the electric connections.

Referring first to Fig. 1, there is shown at 5 the flywheel corresponding to the inertia element of a conventional engine starting mechanism of the inertia type as is shown, for example, in Fig. 4 of Patent No. 1,833,948 to Raymond P. Lansing, granted December 4, 1931; the said flywheel 5 being rotatable in bearings 6 and having integrated therewith a toothed portion 7 constituting a pinion adapted to mesh with and drive a gear train, such as the gear train 81, 85, 84, etc. of the Lansing patent above referred to, for the purpose of transmitting to the crankshaft of the engine to be started the kinetic energy previously stored in flywheel 5. The means for energizing the flywheel 5 is shown as including an electric motor having an armature 8 provided with a central shaft 10 and windings 9 terminat-

ing in the conventional manner in a commutator 11. The field windings of the motor are shown diagrammatically at 12, and the armature shaft is shown as being rotatably supported at 5 one end in bearings 13 located at the righthand end of the armature shaft. While the rotatable support for the opposite end of the armature assembly is not illustrated, a space to receive such a bearing is indicated at 14. The armature shaft 10, near its lefthand end, has drivably secured thereto a flanged sleeve or plate 16 provided with angularly spaced holes adapted to align with correspondingly spaced holes 17 formed in a clutch element 18 of magnetic material, and driving pins 19 are secured to the plate 16 and pass loosely through the apertures 17 of the clutch element 18 to cause the latter to rotate with the plate 16 in response to rotation of the armature 8, while the loose fit of the pins 19 in the holes 17 at the same time permits relative longitudinal motion to a limited extent between the members 16 and 18, while continuing the driving relationship therebetween.

The clutch element 18 is shown as provided 25 with an outwardly flaring flange 21 having a surface adapted to frictionally grip the corresponding surface of the starter flywheel 5 (or, if preferred, intermeshing teeth may be provided on these surfaces) and thus transmit to the member 30 5 the energy developed by reason of closure of the circuit leading to the motor 8, 12 from the source 23. A relay 24 having contacts 26, 27 and 28 controls the passage of current from the source 23 to the windings 8 and 12, the said circuit being normally open by reason of the action of the spring 29 but adapted to be closed, notwithstanding said spring, upon passing of current through the winding of the relay in response to manual closure of the switch 31.

The novel coupling means of the invention includes an electromagnetic apparatus comprising a winding 36 secured to and surrounding a core or spool 37 adapted to be driven by the armature shaft 10 to which the said spool is keyed as indicated at 41; the said winding 36 having electrical connection with the source of current 23 by a path which includes segments 46 and 47 of the motor commutator 11, the ends of the windings 36 being actually passed through separate slots of the armature assembly 8 as indicated at 48 and 49 in Fig. 1. By passing the solenoid winding leads through the slots of the armature in this novel manner, I avoid the necessity of resorting to collector rings or other relatively moving contact making elements and utilize instead

the commutator 11 and the conventional assembly of commutator engaging brushes. In other words, the brushes 60 (which are necessarily provided for the purpose of energizing the conventional armature windings) are also utilized, in accordance with my invention, for the purpose of energizing the winding 36 of the electromagnetic clutch assembly.

Passage of current through the winding 36 energizes the magnetic circuit which includes the core or spool 37 and its head piece 52, the face of the flywheel 5, the flange 21 of the clutch element 18 and the inwardly extending portion 53 of said clutch element 18. The magnetic excitation thus created serves to draw the said portion 53 of the clutch element 18 toward the end surface of the core 37 against the yielding opposition of the coiled spring 59, and this movement is sufficient to bring about a positive gripping action as between the flange 21 of the element 18, on the one hand, and the surface of the flywheel 5 on the other. As the commutator brushes which energize the windings 8 and 12 simultaneously energize the winding 36 of the clutch assembly, it will be apparent that driving relationship is established between the motor and the flywheel 5 simultaneously with the energization of the motor, and such driving relationship will be maintained until both the motor windings and the solenoid winding 36 are simultaneously de-energized by the reopening of the controlling switch 31 and the relay contact 27 controlled thereby. When such reopening of the circuit occurs, the spring 59 is of course effective to break the driving relationship between the surfaces 21 and 5, and thus free the flywheel of any mechanical connection with the motor during the subsequent period of transfer of the stored energy from the flywheel 5 to the engine to be started (in the manner well known in the art and described at length in the Lansing patent above referred to).

In other words, the sequence of actions is as follows:

First: Movement of the motor-actuated rotating member 21 into engagement with flywheel 5, to accelerate the latter.

Second: Return of member 21 to the free position (that is, the position shown in Fig. 1) after the flywheel 5 has been accelerated sufficiently.

Third: Transfer of the stored flywheel energy to the engine to be started (as by engaging clutch elements 8 and 9 of the Lansing Patent 1,833,948 above referred to).

With such a sequence it will be seen that, no matter how "cold" the engine to be started may be, the cranking thereof is by means of energy stored in the flywheel 5 during that preliminary period (listed first above) when there is no me-

chanical connection of the flywheel 5 to the engine to be started. It follows that the member 21 is never called upon to operate against the static inertia resistance of the "cold" engine, but only against the relatively light resistance presented by the unloaded flywheel 5. The flywheel remains unloaded until fully accelerated, at which time the circuit is broken (manually) and member 21 is thus moved to the free position by spring 59, as above explained.

What is claimed is:

1. The combination, with a flywheel to be accelerated, of accelerating means comprising a source of current, an electric circuit including said source, an electric motor having an armature whose windings constitute part of said circuit, said motor also having a commutator to which said windings connect, means for mechanically connecting said armature with said flywheel, said means including a clutch element shiftable to a flywheel engaging position, electromagnetic means for shifting said clutch element, said electromagnetic means including a magnet coil whose ends pass along the armature, in slots of said armature, and terminate in said commutator energizing said electromagnetic means.

2. The combination, with a flywheel to be accelerated, of accelerating means comprising a source of current, an electric circuit including said source, an electric motor having an armature whose windings constitute part of said circuit, said motor also having a commutator to which said windings connect, means for mechanically connecting said armature with said flywheel, said means including a clutch element shiftable to a flywheel engaging position, electromagnetic means for shifting said clutch element, and means including a magnet coil rotatable with said armature and a part of said commutator for energizing said electromagnetic means, said energizing means further including leads passing through said armature in positions parallel to said armature windings.

3. The combination, with a flywheel to be accelerated, of accelerating means comprising a source of current, an electric circuit including said source, an electric motor having an armature whose windings constitute part of said circuit, said motor also having a commutator to which said windings connect, means for mechanically connecting said armature with said flywheel, said means including a clutch element shiftable to a flywheel engaging position, electromagnetic means including a coil rotatable with said armature for shifting said clutch element, and means including a part of said commutator for energizing said electromagnetic means.
